UNITED STATES PATENT OFFICE

RUDOLF MAUSER, OF COLOGNE-MARIENBURG, GERMANY

BUNG FOR IRON TRANSPORT CASKS

Application filed November 28, 1928, Serial No. 322,416, and in Germany September 23, 1927.

This invention relates to a hollow sheet metal bung for iron transport casks, oil drums and the like. Bungs of this type are known, in which the hollow screw-threaded portion 5 of the bung is covered by a plate which comprises means for the engagement of a key for unscrewing the bung.

Now in bungs of this kind the cover plate and the screw-threaded portion of the bung 10 have hitherto been united by the cover plate embracing with its margin, which serves as a packing surface, the collar of the screw-threaded portion, but this gives rise to the possibility of small quantities of the contents 15 of the cask leaking into the interior of the hollow bung. This however not merely involves a loss of the said contents but also leads to contamination of the bung, and this contamination will be increased if moisture can 20 penetrate into the interior of the bung through an aperture provided in the cover plate for a key.

This objection is removed according to the present invention, by turning the upper edge 25 of the screw-threaded portion of the bung over to form a sealing or packing flange which grips the cover plate. The cover plate is provided with a closed depression for the insertion of a key.

When the cover plate is made in polygonal 30 form the corners thereof may be so shaped as to form eyes for lead sealing purposes.

The invention is illustrated by way of example in the accompanying drawings, where- 35 in

Figure 1 shows the bung in plan, and Figure 2 in cross section.

In these drawings, *a* is a cylindrical screw-threaded sleeve secured to the wall *b* of the 40 cask by folding their edges together, as shown in Fig. 2. *c* is the hollow screw-threaded portion of the bung, adapted to screw into the sleeve *a*. The upper edge of the member *c* is bent outwards to form a packing flange *c*¹. The peripheral portions 45

f of the packing flange *c*¹ are bent round the outer edges of the cover plate *d*. At the corners of the cover plate *d* are formed eyes *g* for lead sealing purposes, the peripheral portions of the flange *c*¹ being formed with 50 gaps at the positions of the said sealing eyes. *h* is a depression, preferably oblong in form, in the cover plate *d*, for the insertion of a key for the purpose of rotating the screw-threaded bung. 55

A packing washer *i* may be inserted if desired between the external surface of the cask and the flange *c*¹.

What I claim is:—

1. A hollow bung for iron transport casks, 60 consisting of two pieces of sheet metal, one forming a polygonal top cover plate formed with eyes projecting at the corners for lead sealing purposes, and the other comprising a screw-threaded portion adapted to be 65 screwed into the cask, and an outwardly turned packing flange at the upper end of the screw-threaded portion, the outer edge of the said flange being bent upwards and inwards round the edges of the cover plate. 70

2. A hollow bung for iron transport casks, 75 consisting of two pieces of sheet metal, one forming a polygonal top cover plate formed with eyes projecting at the corners for lead sealing purposes, and with a closed non-circular depression adapted to engage with a key for the purpose of rotating the bung, and the other comprising a screw-threaded portion adapted to be screwed into the cask, and an outwardly turned packing flange at the upper 80 end of the screw-threaded portion, the outer edge of the said flange being bent upwards and inwards round the edges of the cover plate.

3. A hollow bung for iron transport casks, 85 consisting of two pieces of sheet metal, one forming a polygonal top cover plate formed with eyes projecting at the corners for lead sealing purposes and with a closed oblong depression adapted to engage with a key for 90

the purpose of rotating the bung, and the other comprising a screw-threaded portion adapted to be screwed into the cask, and an outwardly turned packing flange at the upper 5 end of the screw-threaded portion, the outer edge of the said flange being bent upwards and inwards round the edges of the cover plate.

In testimony whereof I have signed my
10 name to this specification.

RUDOLF MAUSER.
